WILLIAM MERRELL, OF KENT, OHIO.

Letters Patent No. 83,985, dated November 10, 1868.

IMPROVEMENT IN IRON FENCE-POST.

The Schedule referred to in these Letters Patent and making part of the same.

To all whom it may concern:

Be it known that I, WILLIAM MERRELL, of Kent, in the county of Portage, and State of Ohio, have invented a new and improved Iron Fence-Post; and I do hereby declare that the following is a full, clear, and exact description thereof, which will enable others skilled in the art to make and use the same, reference being had to the accompanying drawings, forming a part of this specification, in which—

Figure 1 is a front view of my invention.

Figure 2 is a side view of the same.

Similar letters of reference indicate corresponding parts.

The object of this invention is to furnish a fence-post which is simple, durable, cheap, and efficient.

It consists of a flat metallic fence-post, usually of iron, and provided with groups of studs for receiving and holding the planks or horizontal parts of the frame.

The post, A, is of cast-iron, and is provided with the groups of studs, *a a a a a*, five or more, arranged as shown, and within which studs the ends of the wooden planks or boards, B, fit with snug contact.

The proximate ends of the planks are further secured by nails driven obliquely through both planks, as shown, the said nails passing through holes previously formed in the post, or cast in the same when the posts are made.

The base of the post is pointed, formed with lateral wings, C C, for the purpose of conferring more stability to the same when in the ground.

I do not wish to claim specially forming wings on the lower portion of a metallic fence-post, as I am aware that this is not new, H. T. Dewey's patent, of May 10, 1859, embodying such construction; but having thus described my invention,

What I claim as new, and desire to secure by Letters Patent, is—

The fence-post A, formed with groups of studs, *a a a a a*, holes *c*, and wings C, all substantially as and for the purpose set forth.

WILLIAM MERRELL.
